UNITED STATES PATENT OFFICE.

CLAYTON A. DUNHAM, OF GLENCOE, ILLINOIS, ASSIGNOR TO DUNHAMETER CORPORATION, OF CHICAGO, ILLINOIS.

DESIGN FOR A TEMPERATURE INDICATOR FOR AUTOMOBILES.

Application filed January 18, 1926. Serial No. 16,146. Term of patent 7 years.

To all whom it may concern:

Be it known that I, CLAYTON A. DUNHAM, a citizen of the United States, residing at Glencoe, in the county of Cook, State of Illinois, have invented a new, original, and ornamental Design for Temperature Indicator for Automobiles, of which the following is the specification, reference being had to the accompanying drawing, forming part thereof, in which—

Fig. 1 is a front elevation of the tem-

perature indicator, as seen from in front of the automobile.

Fig. 2 is a rear elevation of the temperature indicator, as seen from the driver's seat.

Fig. 3 is a side elevation of the indicator on a somewhat larger scale.

I claim:

The ornamental design for a temperature indicator for automobiles, as shown.
